ROY G. STANBROUGH, OF GLENDALE, CALIFORNIA, ASSIGNOR OF ONE-THIRD TO HARRY J. MCCOY, OF INGLEWOOD, CALIFORNIA, AND ONE-THIRD TO VIRGIL K. HALDEMAN, OF HOLLYDALE, CALIFORNIA

TILE BOARD

Application filed April 2, 1930. Serial No. 440,980.

This invention relates to and has for a principal object the provision of an improved method and means for mounting tile on sheets or panels for use in ornamenting, finishing or decorating interior wall surfaces.

My invention comprehends the arrangement of tile in ornamental or decorative effects on a substantially non-expansible sheet of material such as ply wood, plaster, or composite material such as position lath, or other material, whereby the tile may be applied to a wall in prearranged panels more economically than by the ordinary methods of individually applying the tile as in ordinary cases.

It is also an object of my invention to provide a tile structure comprising a substantially non-expansible back which is first coated with a semi-plastic adhesive substance and is thereafter covered with a sheet or sheets of fabric such as burlap to which the hard tiles are applied by first coating the outer surface of the fabric with a like cement and pressing the tiles firmly onto the fabric. Thus I am enabled to provide a fabric cushion which is more or less flexible and expansible between the substantially non-expansible back and the hard tiles.

The cement employed for attaching the fabric to the back and the tiles to the fabric is moisture-proof so as to exclude moisture from the back or carrier.

Other objects may appear as the description progresses.

I have illustrated my invention in the accompanying drawing, in which

Fig. 1 is a plan or face view of a portion of a tile panel constructed in accordance with my invention.

Fig. 2 is an enlarged transverse section of the same on line 2-2 of Fig. 1, showing a sheet of fabric employed as a cushion between the tile and the supporting surface.

Fig. 3 is a view similar to Fig. 2 showing a fibrous cushion between the back and tile in

lieu of the fabric or woven material shown in Fig. 2.

Fig. 4 is a view similar to Fig. 2 but showing a back formed of plaster board for composite material such as is used for wall board, lath, and the like, in lieu of the wood backing shown in Figs. 2 and 3.

In the practice of my invention, I propose to utilize multiple ply wood sheets 1, as shown in Figs. 2 and 3, or plaster board or sheets of composite material in lieu of the ply board, as shown in Fig. 4. When the ply board is used as a back it may consist of a plurality of plies, as at 2, 3 and 4 with the grain of the alternate sheets or plies arranged at right angles to each other.

Thus the wood back 1 is substantially non-expansible. The backs 1 are then coated to a sufficient thickness with a semi-plastic cement, as at 5, after which a sheet or sheets of coarsely woven fabric 6, such as burlap or fibrous material such as felt, are applied to the coating 5 of cement, and by suitable means are smoothed out by pressure or otherwise so as to present a smooth surface for the reception of the blocks of tile.

The fabric or fibrous material 6 forms an expansible cushion material for the tile blocks, and said blocks are applied to the fabric or fibrous material 6 by thoroly coating the outer surface of the material 6 with a semi-plastic cement as at 7, after which the tile blocks 8 are applied as shown in the drawings. The usual pointing 9 of suitable material may be employed between the tile blocks 8.

The cement employed for attaching the material 6 to the back 1 and also for attaching the tile blocks to the material 6 is semi-plastic in character, i. e. to say, after the cement has hardened it will still retain a certain amount of flexibility or ductility. Preferably the cement embodies certain vegetable and mineral ingredients for lending tenacity, body, and resiliency thereto. The cement

employed should also be of such character that it will adhere equally as well to composition materials as to wood, and should be waterproof and bacteria-proof so as to prevent deterioration of the tile panels after they have been set up in a wall.

The back 1 should be of such character that it will be proof against distortion, warping, swelling, expansion and contraction in order to prevent the cracking or breaking apart of the tile blocks on the panels.

The exposed surfaces of the back 1 may be coated with any suitable material such as shellac to prevent the entrance of moisture into the pores of the backing material. At the edges of the composite panels the cement may overlap the edge of the cushion material 6 so as to prevent the entrance of moisture thereto.

It will be apparent that an assembled tile panel of the character shown and described will be proof against warping, distortion or breakage of the tile by reason of the interposition between the back and the tiles of the resilient, flexible and expansible sheets of material 6. Said material being loosely woven or fibrous, is of itself highly flexible, resilient and expansible, but when held between the two coatings 5 and 7 of semi-plastic cement these characteristics of the material 6 are substantially modified, and the tendency to stretch and distort are counteracted. The semi-plastic cement coats 5 and 7, however, being somewhat resilient, permit of a sufficient expansion and contraction of the material 6 to offset any change which may be effected by moisture or any slight expansion or contraction of the back 1 by changes of temperature or conditions of extreme dryness or extreme moisture.

The method and means for constructing tile panels which have been illustrated and described herein are therefore admirably adapted for use in producing interior decorative effects as well as for exterior use, and the construction of the panels at the factory in predetermined designs and in suitable sizes substantially reduces the cost of applying a tile finish to wall surfaces.

While ply wood or composition panels, as at 1, are substantially stiff and proof against warping and distortion, I may provide any suitable means on the backs of said panel for additionally stiffening the same, as taught by others in the art.

Other objects and advantages will readily appear to those familiar with the design, structure and use of such structures.

What I claim is:

1. A wall structure comprising a panel having a non-expansible back, a cushion of fibrous material adhesively applied to said back, and a facing of tile adhesively applied to the outer surface of said cushion material.

2. A wall structure comprising a panel

formed of a substantially non-expansible back, a coating of semi-plastic cement on a surface thereof, a sheet of fibrous material applied over said coating of cement, a coating of semi-plastic cement over the surface of said fibrous material, and a facing of tile applied to said last mentioned coating of cement.

3. A wall structure comprising a panel formed of a substantially non-expansible back, a fibrous cushion applied to a surface of said back, a coating of semi-plastic cement applied to the outer surface of said cushion, and a facing of tile applied to said coating of cement.

4. A wall structure comprising a panel formed of a substantially non-expansible back, a coating of semi-plastic cement applied over a surface thereof, a sheet of expansible material applied over said coating of cement, and a facing of tile affixed to the outer surface of said expansible material.

5. A wall structure comprising a panel formed of a sheet of non-flexible material, a sheet of expansible material interposed between layers of semi-plastic cement applied to a surface of said back, and a tile facing applied to said expansible material.

ROY G. STANBROUGH.
